RECORD

Edward Kirby Bottle, deceased, late of Elmira, N. Y., by Sara Jane Bottle, administratrix, Elmira, N. Y., assignor to American Sales Book Company, Limited, a corporation of Canada

Application March 18, 1931. Serial No. 523,428

4 Claims. (Cl. 282—12)

This invention relates to a functionally and structurally improved record capable of use in numerous different associations, but primarily intended to be inscribed by a writing implement such as a pen or pencil and in some instances a typewriter, to provide simultaneously by a single operation a plurality of records.

A further object of the invention is that of constructing an article of this nature which may readily be manipulated and efficiently inscribed, and in which after such inscription, the record elements may readily be separated from each other.

Another object is that of furnishing a record which may be constructed largely by automatic machinery and without the use of skilled labor so that an article is provided which may be manufactured and sold at a relatively nominal figure.

With these and other objects in mind, reference is had to the attached sheets of drawings, illustrating practical embodiments of the invention, and in which:

Fig. 1 shows a record ready to have its parts separated;

Fig. 2 is a similar view showing the parts in process of separation;

Fig. 3 is an enlarged transverse sectional view taken along the lines 3—3 and in the direction of the arrows of Fig. 1;

Fig. 4 is a view similar to the first figure, but showing a slightly different form of construction;

Fig. 5 is a view corresponding to Fig. 2, but showing the structure as illustrated in Fig. 4; and

Fig. 6 is a fragmentary transverse view taken along the lines 6—6 and in the direction of the arrows of Fig. 4.

In the embodiments illustrated, the invention has been shown in connection with a record embracing three inscription receiving surfaces, and two transfer layers. It is obvious that any desired number of layers of both types might be employed. Additionally, the outermost layers have been shown as connected to each other and in fact, forming integral parts secured together along their upper edges. While in many respects, according to the present invention, this is desirable, nevertheless, it will be understood that this connection might be of any desired character disposed adjacent or along any edge of the record, or might, in fact, under certain conditions, be entirely dispensed with.

Thus, in these views, the numerals 10, 11 and 12 indicate inscription receiving layers, the first and last of which as afore brought out are con-

nected along their upper edges, at which point they may be provided with a score line 13 so as to be capable of ready segregation. The layer 11 is in the form shown loosely disposed between the layers 10—12 and there is interposed between these latter layers and the layer 11, layers of transfer material 14 such as ordinary carbon paper. With a construction of this nature, it is apparent that the inscriptions may readily be made upon the uppermost surface and carried through to the surfaces 11 and 12 of the record. The layers 10—12 being folded upon themselves provide what might be termed an envelope, neatly and compactly housing the intervening layers. After such inscription, however, difficulty may be experienced in quickly removing the carbon or transfer layers, while retaining as a unit, or group the inscribed layers.

With a view to overcoming difficulties in this connection, it will be observed that as in Figs. 1 to 3, transfer layers may have a corner of their bodies removed as at 15 in order to provide grip escaping apertures. In order to avail oneself of this construction, it is desirable that portions of the carbon or transfer layers be rendered accessible for the purpose of gripping the same and effecting their segregation. With a view to achieving this, in the figures under consideration, the inscription layers are formed with openings 16 which may be utilized for retaining one or more of the record group in association with a binder or file. Obviously, the bottom layer need not necessarily be perforated, but it is preferred for convenience of manufacture that the openings be formed through the entire record.

These openings or opening may be of any desired configuration so long as they have sufficient length or area, in the direction in which the layers are to be projected or displaced, that these layers may be manipulated accordingly. In other words, still referring to the figures last identified, assume after inscription that the point of a pencil is directed through the opening 16 so as to firmly engage the layers of transfer material and this pencil is thereupon moved sideways. It will be obvious as in Fig. 2 that the edges of the transfer layers will be projected. During the foregoing operation, the inscribed layers are grasped in line with the grip escaping apertures 15. Accordingly, the displacement or projection of the transfer layers is in no wise interfered with. Thereafter, while maintaining the grip on the inscribed layers, the projected portions of the transfer layers may be gripped and these layers may be withdrawn completely from the record, leaving how-

ever, the inscribed layers properly disposed with respect to each other or in other words maintained as a group.

In view of the foregoing disclosure, it will be noted that the apertures or openings 16 are entirely enclosed, that is, they are spaced within the edges of the layers or sheets and do not open through said edges at any point. These openings are thus positioned to avoid mutilation of the sheet edges; they are protected from damage by the intervening areas of paper between them and the sheet edges; they may be made relatively small, thus avoiding mutilation of the paper and encroachment upon the record area; and they may be utilized as binding or filing apertures after serving their function in sheet separation. Since the openings 16 are utilized for separating the record sheets from the carbon or transfer sheets, they are herein referred to as sheet-separating openings. Furthermore, it will be noted that the grip escaping apertures 15 of the transfer sheets are normally aligned, when the sheets are in register with each other, and with areas of the record sheets, herein termed grip areas, whereby the record sheets may be selectively gripped to the exclusion of the transfer sheets. The set of openings 16 adjacent to the selective grip escaping apertures or notches 15 are spaced only slightly inwardly from the edges of said grip escaping notches. Also, this set of openings is positioned substantially on a straight line between the other set of openings 16 and the grip escaping notches 15. It will, therefore, be seen, as in Fig. 2, that one set of openings 16 will be brought into alignment with the grip escaping notches 15 when the transfer sheets are separated in a direction along a straight line between openings 16 and notches 15 a distance equal to the diameter of the openings 16. Thus, when the pencil or other pointed instrument is inserted as shown in Figs. 1 and 2, and the sheets separated by this means, a distance equal to the diameter of the openings 16, one set of openings 16 will thus be brought into alignment with the notches 15. In this manner a pencil or other instrument may be inserted into the openings 16 thus aligned, and through the notches 15, thus holding the sheets in their partially separated position, as shown in Fig. 2. The protruding edges of the transfer sheets may subsequently be gripped and the separation of the sheets completed.

In the form of construction shown in Figs. 4 to 6, the grip escaping apertures 17 may be disposed in the record corner opposite from that in which they are located in connection with the structure of Figs. 1 to 3. Additionally, the apertures or openings 17 are, instead of being round, oblong. Therefore, by the use of an implement as shown in Fig. 5, sidewise displacement may be achieved and the record parts may be supported in the same manner as that which has been heretofore described.

Thus, among others, the several objects of the invention as specifically afore noted are achieved. It will be appreciated that numerous changes in construction and rearrangements of the parts might be resorted to without departing from the spirit of the invention as defined by the claims.

Having described the invention, what is claimed as new and desired to secure by Letters Patent, is:

1. A record assembly including record sheets in superposed manifolding relation with each other, a transfer sheet in interleaved transfer relation

with said record sheets, each of said record sheets having a sheet separating opening entirely enclosed therein, and said openings being in register with each other and with unapertured areas of said transfer sheet when all of said sheets are registered in the assembly, said transfer sheet having a grip escaping aperture opening through its edge and positioned in the assembly remote from said sheet separating openings and in register with grip areas of said record sheets, each of said record sheets having also a second opening entirely enclosed therein and spaced from the respective sheet separating openings and in register with each other when the record sheets are registered, said second openings being positioned in the assembly substantially on a straight line between said sheet separating openings and said grip escaping apertures and being in alignment with the latter when the record and transfer sheets are separated from each other along said straight line a distance equal to the diameter of said sheet separating openings, said first and second openings of each record sheet being equally spaced inwardly a short distance from one of the sheet margins to provide a pair of spaced filing apertures for each record sheet.

2. A record assembly including set of record sheets and a set of transfer sheets in superposed manifolding relation with each other, each of the sheets of one of said sets having a sheet separating opening entirely enclosed therein and said openings being in register with each other and with unapertured areas of the other set of sheets when all of said sheets are registered in the assembly, each of said openings being positioned adjacent to but spaced inwardly a short distance from one margin of its sheet so as to provide a filing aperture for the latter, and each of the sheets of the second of said sets having a grip escaping aperture opening through its edge and positioned in the assembly remote from said sheet separating openings and in register with grip areas of said one set of sheets.

3. A record assembly including a transfer sheet between superposed record sheets, one of the record sheets having a sheet separating opening entirely enclosed therein and in register with an unapertured area of said transfer sheet, said opening being positioned adjacent to but spaced inwardly a short distance from one margin of its sheet, said transfer sheet having a grip escaping aperture opening through its edge and positioned in the assembly remote from said sheet separating opening and in register with grip areas of said record sheets.

4. A record assembly including a transfer sheet between superposed record sheets, one of the record sheets having a sheet separating opening entirely enclosed therein and in register with an unapertured area of said transfer sheet, said opening being positioned adjacent to but spaced inwardly a short distance from one margin of its sheet, said transfer sheet having a grip escaping aperture opening through its edge and positioned in the assembly remote from said sheet separating opening and in register with grip areas of said record sheets, two of said record sheets being superposed folds of an integral folded sheet.

SARA JANE BOTTLE,
Administratrix of the Estate of Edward Kirby
Bottle, Deceased.
